UNITED STATES PATENT OFFICE.

EDWARD ALBERT CUNNINGHAM, OF AMBRIDGE, PENNSYLVANIA.

METHOD OF TREATING PHOTOGRAPHIC PAPER.

No. 895,970.

Specification of Letters Patent.

Patented Aug. 11, 1908.

Application filed April 9, 1908. Serial No. 426,001.

To all whom it may concern:

Be it known that I, EDWARD ALBERT CUNNINGHAM, of Ambridge, in the county of Beaver and State of Pennsylvania, have invented a new and useful Method of Treating Photographic Paper, of which the following is a specification.

My invention relates to photographic paper and has for its object the economical treatment of photographic paper, so that prints of any suitable color may be made, and other prints made from those first treated.

A further object is to provide a cheap and efficient photographic paper which will be unaffected by sunlight and other climatic conditions.

My invention is specially adapted for the treatment of the paper used in what is known as the "blue printing" process, since by its application I am able to change the actinic blue color of the prints to a non-actinic color.

In carrying out my invention I treat the prints, after being washed, with a solution or solutions of a salt of one or more of the elements, preferably of the double salts of copper and potassium chlorid, thereby coating those portions of the prints which have been acted on by light. The print is then washed and transferred to a solution or solutions of at least one of the sulfids or thio-sulfates, preferably the sulfid of sodium, which changes the coating obtained by the first treatment into a sulfid of the element or elements used. The print is then washed or dried in the usual manner. If the double salts of copper are used in the coating treatment, then, when the print is subsequently treated by the sulfids or thio-sulfates, the double salts of copper will accordingly be changed into sulfids of copper.

Those skilled in the art may vary the method of treatment described above without departing from the scope and spirit of my invention, since

What I claim is:

1. The herein described method of treating photographic paper, which consists in placing a photographic print in a solution containing salts of one of the metals, where-

by said print is coated with said salts, and then treating said print with a solution which will change the deposited metal into a sulfid.

2. The herein described method of treating photographic paper, which consists in placing a photographic print in a solution containing a salt of copper, whereby said print is coated with said copper and transferring said print into a solution which will change the deposited copper into a sulfid. 55

3. The herein described method of treating photographic paper, which consists in placing a photographic print in a solution containing double salts of copper and potassium chlorid whereby the print is coated with said salt, and then subjecting said print to a solution which will change the deposited copper into a sulfid of copper. 65

4. The herein described method of treating photographic paper, which consists in placing a photographic print in a solution containing a salt of one of the metals, whereby said print is coated with said salts, and transferring said print into a solution containing a salt of sodium, whereby the salt of the metal is changed into a sulfid. 70

5. The herein described method of treating photographic paper, which consists in placing a photographic print in a solution containing a salt of one of the metals, whereby said print is coated with said salt, washing said print, and inserting said print into a second solution containing a sulfid, whereby said sulfid acts on the coating on said print to change said salt in said coating into sulfid, 80 and then washing and drying the print. 85

6. The herein described method of treating photographic paper, which consists in immersing a photographic print in a solution containing the double salts of copper and potassium chlorid, and subsequently subjecting it to a solution containing a salt of sodium. 90

In testimony whereof, I have hereunto set my hand.

EDWARD ALBERT CUNNINGHAM.

Witnesses:

ARTHUR P. HUME,
LEE C. JONES.
